US00D852305S

(12) **United States Design Patent** (10) **Patent No.:** **US D852,305 S**
Parsons et al. (45) **Date of Patent:** **** Jun. 25, 2019**

(54) GOLF CLUB HEAD	1,306,029 A	6/1919	Robertson
(71) Applicant: PARSONS XTREME GOLF, LLC, Scottsdale, AZ (US)	D55,867 S	7/1920	Mattern
	1,534,600 A *	4/1925	Mattern .....
			A63B 53/08
			473/337
(72) Inventors: Robert R. Parsons , Scottsdale, AZ (US); Bradley D. Schweigert , Anthem, AZ (US); Michael R. Nicolette , Scottsdale, AZ (US)	1,538,312 A	5/1925	Beat
	D94,549 S *	2/1935	Jansky .....

CLAIM

The ornamental design for a golf club head, as shown and described.

DESCRIPTION

FIG. 1 is a top perspective view of a golf club head;
 FIG. 2 is a bottom perspective view of the golf club head of FIG. 1;
 FIG. 3 is a front elevational view of the golf club head of FIG. 1;
 FIG. 4 is a rear elevational view of the golf club head of FIG. 1;
 FIG. 5 is a top view of the golf club head of FIG. 1;
 FIG. 6 is a bottom view of the golf club head of FIG. 1;
 FIG. 7 is a left side view of the golf club head of FIG. 1;
 FIG. 8 is a right side view of the golf club head of FIG. 1;
 FIG. 9 is a top perspective view of a second embodiment of a golf club head;
 FIG. 10 is a bottom perspective view of the golf club head of FIG. 9;
 FIG. 11 is a front elevational view of the golf club head of FIG. 9;
 FIG. 12 is a rear elevational view of the golf club head of FIG. 9;
 FIG. 13 is a top view of the golf club head of FIG. 9;
 FIG. 14 is a bottom view of the golf club head of FIG. 9;
 FIG. 15 is a left side view of the golf club head of FIG. 9;
 FIG. 16 is a right side view of the golf club head of FIG. 9;
 FIG. 17 is a top perspective view of a third embodiment of a golf club head;
 FIG. 18 is a bottom perspective view of the golf club head of FIG. 17;
 FIG. 19 is a front elevational view of the golf club head of FIG. 17;
 FIG. 20 is a rear elevational view of the golf club head of FIG. 17;
 FIG. 21 is a top view of the golf club head of FIG. 17;

FIG. 22 is a bottom view of the golf club head of FIG. 17;
 FIG. 23 is a left side view of the golf club head of FIG. 17;
 FIG. 24 is a right side view of the golf club head of FIG. 17;
 FIG. 25 is a top perspective view of a fourth embodiment of a golf club head;
 FIG. 26 is a bottom perspective view of the golf club head of FIG. 25;
 FIG. 27 is a front elevational view of the golf club head of FIG. 25;
 FIG. 28 is a rear elevational view of the golf club head of FIG. 25;
 FIG. 29 is a top view of the golf club head of FIG. 25;
 FIG. 30 is a bottom view of the golf club head of FIG. 25;
 FIG. 31 is a left side view of the golf club head of FIG. 25;
 FIG. 32 is a right side view of the golf club head of FIG. 25;
 FIG. 33 is a top perspective view of a fifth embodiment of a golf club head;
 FIG. 34 is a bottom perspective view of the golf club head of FIG. 33;
 FIG. 35 is a front elevational view of the golf club head of FIG. 33;
 FIG. 36 is a rear elevational view of the golf club head of FIG. 33;
 FIG. 37 is a top view of the golf club head of FIG. 33;
 FIG. 38 is a bottom view of the golf club head of FIG. 33;
 FIG. 39 is a left side view of the golf club head of FIG. 33;
 FIG. 40 is a right side view of the golf club head of FIG. 33;
 FIG. 41 is a top perspective view of a sixth embodiment of a golf club head;
 FIG. 42 is a bottom perspective view of the golf club head of FIG. 41;
 FIG. 43 is a front elevational view of the golf club head of FIG. 41;
 FIG. 44 is a rear elevational view of the golf club head of FIG. 41;
 FIG. 45 is a top view of the golf club head of FIG. 41;
 FIG. 46 is a bottom view of the golf club head of FIG. 41;
 FIG. 47 is a left side view of the golf club head of FIG. 41;
 FIG. 48 is a right side view of the golf club head of FIG. 41;
 FIG. 49 is a top perspective view of a seventh embodiment of a golf club head;
 FIG. 50 is a bottom perspective view of the golf club head of FIG. 49;
 FIG. 51 is a front elevational view of the golf club head of FIG. 49;
 FIG. 52 is a rear elevational view of the golf club head of FIG. 49;
 FIG. 53 is a top view of the golf club head of FIG. 49;
 FIG. 54 is a bottom view of the golf club head of FIG. 49;
 FIG. 55 is a left side view of the golf club head of FIG. 49;
 FIG. 56 is a right side view of the golf club head of FIG. 49;
 FIG. 57 is a top perspective view of an eighth embodiment of a golf club head;
 FIG. 58 is a bottom perspective view of the golf club head of FIG. 57;
 FIG. 59 is a front elevational view of the golf club head of FIG. 57;
 FIG. 60 is a rear elevational view of the golf club head of FIG. 57;
 FIG. 61 is a top view of the golf club head of FIG. 57;
 FIG. 62 is a bottom view of the golf club head of FIG. 57;
 FIG. 63 is a left side view of the golf club head of FIG. 57;
 and,
 FIG. 64 is a right side view of the golf club head of FIG. 57.

The broken line showing is included for the purpose of illustrating unclaimed subject matter and forms no part of the claimed design.
